UNITED STATES PATENT OFFICE.

FREDERIC EUGENE IVES, OF PHILADELPHIA, PENNSYLVANIA.

PHOTOCHROMOSCOPIC APPARATUS.

SPECIFICATION forming part of Letters Patent No. 655,712, dated August 14, 1900.

Application filed October 7, 1899. Serial No. 732,915. (No model.)

To all whom it may concern:

Be it known that I, FREDERIC EUGENE IVES, a citizen of the United States, residing in Philadelphia, Pennsylvania, have invented 5 certain Improvements in Photochromoscopes and Photochromoscope-Cameras, of which the following is a specification.

My invention consists of a photochromoscope-camera whereby three images of the 10 same size and having the same perspective may be produced simultaneously side by side upon a single plate or upon three plates disposed side by side in the same plane.

The main distinction between my present 15 camera and previous cameras which I have devised consists in its greater simplicity and accompanying cheapness of construction.

The instrument is also available as a photochromoscope.

20 In the accompanying drawings, Figure 1 is a perspective view of a camera constructed in accordance with my invention, illustrating the manner in which it is intended to be used. Fig. 2 is a transverse section of the camera, 25 taken on the line *a a*, Fig. 3, but showing the parts of the camera closed. Fig. 3 is a top or plan view showing the upper portion of the camera thrown back on its hinges. Fig. 4 is a sectional view on the line *b b*, Fig. 2. 30 Fig. 5 is a detached view of a lens-adjusting device forming part of the camera. Fig. 6 is a diagram illustrating the courses taken by the light-rays in my improved camera. Fig. 7 is a diagram showing another embodiment 35 of my invention; and Figs. 8 to 15, inclusive, are diagrams explanatory of one of the features of my invention.

The camera-box comprises a lower portion 1 and an upper portion 2, disposed at a right 40 angle to said lower portion and having a bottom plate 3, which serves as a lid or cover for said lower portion, the two parts being hinged together at 4, so that the upper portion can be thrown back in order to permit ready access 45 to the interior of the portion 1, as shown in Fig. 3. In said portion 1 of the box are arranged sets of primary and secondary reflectors, each set comprising three reflectors and those of the primary set being numbered 5, 50 6, and 7, while those of the secondary set are numbered 5^a, 6^a, and 7^a, respectively. The reflectors of the primary set are inclined in

the same direction and at an angle of forty-five degrees to the axis of the incident rays and are disposed one behind another in the 55 axial line of said incident rays, the first two reflectors 5 and 6 of the set being transparent reflectors, so that they will serve not only to reflect but also to transmit portions of said incident rays. The reflected rays are thrown 60 horizontally at right angles to the axis of the incident rays and are received by the secondary reflectors 5^a, 6^a, and 7^a, these reflectors being disposed diagonally one behind another on a line which is diagonal to the axis of the 65 incident rays and being also disposed at an angle of forty-five degrees to the axis of the reflected rays and so as to reflect said rays upwardly or in a direction at right angles 70 to the rays from the reflectors 5, 6, and 7. 75 This combination permits of the disposal of the secondary reflectors 5^a, 6^a, and 7^a in a straight row, so that three images can be thrown side by side upon the same sensitive plate mounted upon the top of the portion 2 75 of the camera-box or upon three sensitive plates located side by side in the same plane on the top of such portion 2 of the box; but it will be observed on reference to Fig. 4 that the secondary reflectors are in planes which 80 cross at an angle of forty-five degrees the longitudinal line of the sensitive plate or plates. Hence in the absence of some provision for correcting such result the images would be thrown upon the sensitive plate or plates with 85 their horizon-lines disposed diagonally in respect to the longitudinal line of said plate or plates. This defect I overcome, however, by rotating the camera about its optical axis to the extent of forty-five degrees, thereby effecting a corresponding change in the angle 90 of the images, and I retain the camera in this position while the photograph is being taken, a simple means for the accomplishment of this result being the beveled block 8, which 95 serves as a support for the camera and imparts the proper angle thereto, as shown in Fig. 1, although a tripod having a head adjustable to the desired angle or other means of supporting the camera in the desired inclined position might, as will be evident, be substituted for the beveled block 8.

In order that the operation of the camera and the reasons for the peculiar disposition

of its parts may be readily understood, it may be considered as developed on the basis of an arrangement of three separate cameras, as shown in Fig. 8, where A B C are the three cameras and D E F mirrors inclined in a vertical plane at forty-five degrees to the optical axis of the cameras, the mirrors D and E being transparent and the continuation of the line of the optical axes by right-angle reflection at the mirrors making them coincident in the direction of the object beyond G. With this arrangement the images formed in the usual manner at H I J will be on the same plane with the horizontal lines parallel to the base of the camera and joining each other, and a single sensitive plate could be used to receive all of the images. If now there is placed in each camera a forty-five-degree mirror arranged to reflect the images upward, they will be reversed from top to bottom, but will still be on one plane and in line with the horizon-lines parallel to the edges of the plate and joining each other. This arrangement is defective, however, inasmuch as the camera B is optically farther removed from the object than the camera A and the camera C farther than the camera B, with the result that the images are not identical in perspective. For the purpose for which my camera is designed it is necessary that the different images should be identical in perspective. In order to secure this result, cameras would have to be arranged as shown in Fig. 9, wherein the optical distance from G is the same for all of the cameras. With this arrangement the images H I J are identical in perspective and the horizon-lines parallel to the base of the camera, but the images are not on one plane and cannot therefore be received upon a single sensitive plate. If now there be placed in each camera a forty-five-degree mirror arranged to reflect the images upward, they will then be projected on one plane and could be received on a single sensitive plate K, as shown at A', B', and C' in Fig. 10, in which the dotted lines represent the horizon-lines of the images; but if a rectangular plate is used with its edges parallel to the horizon-lines two-thirds of its area will be wasted. A smaller plate could be used by placing it with its edges disposed diagonally to the horizon-lines, as at L in Fig. 11; but much of the area of the sensitive plate would still be wasted and the horizon-lines do not join each other. If, however, a camera constructed to give these three diagonally-disposed horizon-lines, as in Fig. 11, be revolved on its optical axis through an arc of forty-five degrees, the three horizon-lines will become parallel to the edges of the plate forming a single line, as in Fig. 12, if the revolution is in one direction or three parallel lines, as in Fig. 13, if the revolution is in the opposite direction. In either case, if the images are originally large enough to greatly overlap each other in the absence of diaphragms, and diaphragms are so disposed as to make the sides of the rec-

tangular openings parallel to the edges of the sensitive plates, the whole plate may be utilized and the images appear as in Fig. 14 or Fig. 15.

Various forms of secondary reflectors may be employed, the preferable form, however, being a silvered rectangular prism, and in connection with each of the secondary reflectors I also employ a diaphragm 9, the aperture of which is dependent upon the character of the sensitive plate employed and of the special color sensation represented by the rays of light reflected by the mirrors in connection with which the diaphragm is used. Thus, as shown in Fig. 4, the diaphragm employed in connection with the mirrors 5 and 5^a has the smallest aperture, that employed in connection with the mirrors 7 and 7^a has the largest aperture, and that employed in connection with the mirrors 6 and 6^a has an aperture of intermediate size.

The opening 10 in the camera-box for the passage of the incident rays may be closed by a cap of any desired character, that shown in the present instance being a simple hinged flap 11, and said opening may have an appropriate lens, although I prefer to use a separate lens in connection with each of the secondary reflectors, one of these lenses being shown at 12 in Fig. 2. The series of lenses is preferably carried by a frame 13, which is depressed by means of a spring 14, but can be moved against the action of said spring by wedge-bars 15, Fig. 5. Hence adjustment of the lenses 12 toward and from the secondary reflectors is permitted within certain limits for focusing purposes.

The three color-screens 16 used in connection with the photochromoscope-camera may be disposed in any desired position in the path of the light-rays, said color-screens being located in the present instance in the portion 2 of the camera-box. The primary reflectors 5, 6, and 7 are held in contact with suitable stops by means of springs 17, so that they can be readily removed for cleaning or other purposes.

An instrument of the character described is of simple construction. Hence it can be made more cheaply than cameras which I have heretofore devised, while at the same time it is quite as effective for the intended purpose.

The size of the camera may be reduced and the secondary reflector 7^a dispensed with by disposing the reflector 7, as shown in Fig. 7, so that it will reflect the rays in the same direction as the secondary reflectors 5^a and 6^a, the latter in this case being disposed closer to the reflectors 5 and 6 than when the arrangement shown in Fig. 4 is adopted. In this case, however, the horizon-line in the image above the secondary reflector 7 will be disposed at right angles to the horizon-lines in the images above the reflectors 5^a and 6^a.

The instrument may, if desired, be used as a photochromoscope instead of a camera, the direction of the rays of light in such case be-

ing reversed, a chromogram or chromograms taking the place of the sensitive plate or plates upon the top of the portion 2 of the box and receiving the light for illumination 5 and the opening 10 of the box becoming the view-point and being, if desired, provided with a suitable eyepiece. Hence the line of sight in such an instrument is the same as the incident ray in the camera. If, however, the 10 instrument is to be used as a photochromoscope, it is better to omit the lenses 12 and the diaphragms 9 and to make the secondary reflectors relatively larger and to employ a single lens at 10.

15 Having thus described my invention, I claim and desire to secure by Letters Patent—

1. In an instrument of the character described, the combination of a casing, a series 20 of reflectors inclined one behind another in the same line, two of said reflectors being transparent, and a second series of reflectors disposed one behind another in a line which is diagonal to that of the first series of reflectors, 25 substantially as specified.

2. In an instrument of the character described, the combination of a casing, a series 30 of color-screens, a series of reflectors inclined one behind another in the same line, two of said reflectors being transparent, and a second series of reflectors disposed one behind another in a line which is diagonal to that of the first series of reflectors, substantially as specified.

35 3. In an instrument of the character described, the combination of a casing, a series of reflectors inclined one behind another in the same line, two of said reflectors being transparent, and a second series of reflectors disposed one behind another in a line which is diagonal to that of the first series, said second set of reflectors being disposed so as to reflect the rays in a direction at right angles to that in which they are reflected by the 45 transparent reflectors of the first series, substantially as specified.

4. In an instrument of the character described, the combination of a casing, three reflectors inclined one behind another in the 50 same line, two of said reflectors being transparent, and a second series of three reflectors inclined one behind another in a line which is diagonal to that of the first series of reflectors, substantially as specified.

55 5. In an instrument of the character described, the combination of a casing, a series of inclined primary reflectors disposed one behind another in the same line, two of said reflectors being transparent, a series of secondary reflectors disposed in a line diagonal to that of the first series, and means for supporting a sensitive plate or plates in a position diagonal to the axial line of the incident rays, substantially as specified.

6. In an instrument of the character described, the combination of a casing, a series of inclined primary reflectors disposed one behind another in the same line, two of said reflectors being transparent, and a series of secondary reflectors disposed in a line diagonal to that of the first series, and each set in a plane at an angle to the plane of the primary reflectors whereby the reflected images will have their horizon-lines disposed diagonally in respect to the longitudinal line of the 75 series of images, substantially as specified.

7. In an instrument of the character described, the combination of a casing, a series of reflectors inclined one behind another in the same line, two of said reflectors being transparent, a second series of reflectors inclined one behind another in a line which is diagonal to that of the first series, and means for mounting the casing at such an angle that the images produced will have their horizon-lines disposed parallel with or at right angles to the longitudinal lines of the plate or series of plates on which said images are formed, substantially as specified.

8. In an instrument of the character described, the combination of a series of inclined primary reflectors disposed one behind another in the same line, two of said reflectors being transparent, a series of secondary reflectors disposed in a line diagonal to that of the first series, a casing for containing said reflectors, a lens-bar having a lens for each division of the reflected rays, and means for adjusting said lens-bar for focusing purposes, substantially as specified.

9. In an instrument of the character described, the combination of a casing, a series of reflectors inclined one behind another in the same line, two of said reflectors being transparent, a second series of reflectors inclined one behind another in a line which is diagonal to that of the first series of reflectors, and diaphragms of different aperture, one for each image produced, substantially as specified.

10. In an instrument of the character described, a series of inclined primary reflectors disposed one behind another in the same line, two of said reflectors being transparent, a series of secondary reflectors disposed in a line diagonal to that of the first series and a sensitive-plate support inclined at an angle of forty-five degrees from the horizontal when the instrument is in use, substantially as specified.

In testimony whereof I have signed my name to this specification in the presence of two subscribing witnesses.

FREDERIC EUGENE IVES.
